UNITED STATES PATENT OFFICE

2,418,618

HIGH-SPEED TAPE FACSIMILE SYSTEM

Frank R. Brick, Elizabeth, N. J., assignor to
Finch Telecommunications, Inc., Passaic, N. J.,
a corporation of Delaware

Original application May 1, 1943, Serial No.
485,271. Divided and this application February
5, 1944, Serial No. 521,226

5 Claims. (Cl. 178—6.6)

1

This application is a division of my application Serial No. 485,271, filed May 1, 1943, and relates to high speed facsimile transmitting and receiving systems and, more particularly, to tape transmitters and recorders where high speed must be combined with a degree of clarity and intelligibility to enable the rapid sending and receiving of written messages.

In the sending and receiving of facsimile signals, emphasis has more recently been placed on obtaining a record at the receiving end of the system which is of a quality at least equal to that at the transmitting end. This requires close spacing of scanning lines in order to obtain maximum definition together with apparatus which will permit the recording of a large number of shade variations from white to black. While speed of recording of high quality facsimiles has been greatly increased, this speed of reproduction at the receiver is limited by these factors.

In communication to and from moving vehicles such as military vehicles in the field, where it is desired to transmit written messages by facsimile signals, high speed of transmission and recording is the prime essential; for this purpose, among others intelligibility of the message rather than high quality of recording is the prime consideration. Hence scanning lines need no longer be closely spaced to provide for maximum definition; they need only be sufficiently close (say of the order of 60 scanning lines per inch) to ensure intelligibility. Likewise, a large range of tonal variations from white to black need not be provided for; but rather means need only be provided to make a record of one shade or color on a contrasting background.

In such high speed communication between moving vehicles, the apparatus must be compact, light and rugged, must be easily operable, require a minimum of attention (in fact virtually none at all) even while operating, must have a minimum of parts and must be able to withstand the physical shocks incident to operation of a moving vehicle over rough terrain.

It is, therefore, an object of my invention to provide a facsimile transmitting and receiving system which may be operated at high speeds.

It is another object of my invention to provide a portable tape transmitter and recorder which may be operated at high speeds and yet produce a clear and intelligible message.

It is a further object of my invention to provide a compact, light, rugged facsimile transmitting and receiving unit operable from the ordinary radio transmitter and receiver, which is virtually shock-proof, and requires only a minimum of attention by the operator.

2

It is still a further object of my invention to provide a portable high speed tape transmitter and recorder in which only approximate synchronism between transmitting and recording units yet produces a clear and intelligible message.

There are other objects of my invention which, together with the foregoing, will appear in the detailed description in connection with the drawings, which is to follow:

Figure 1 is a top view of the novel recorder of my invention, with the top of the casing removed.

Figure 2 is a side view of the recorder of Figure 1.

Figure 3 is a cross-sectional view on the line 3—3 of Figure 1.

Figure 4 is a view taken on line 4—4 of Figure 3 looking in the direction of the arrows and showing the method of mounting and supporting the armature of the recorder.

Figure 5 is a view taken from line 5—5 of Figure 3 looking in the direction of the arrows and showing the mounting means for the printing blade of my recorder.

Figure 6 is a cross-sectional view taken on line 6—6 of Figure 3.

Figure 7 is a view on line 7—7 of Figure 3 looking in the direction of the arrows and showing the relationship between the armature, printing blade, and recording elements.

Figure 8 is a view, partly in cross-section, taken on line 8—8 of Figure 1 looking in the direction of the arrows.

Figure 9 is a view, partly in cross-section, taken on the line 9—9 of Figure 2 looking in the direction of the arrows and showing the compartment and supply roll for the tape.

Figure 10 is an elevation of the transmitting unit of my invention which is peculiarly adapted to cooperate with the recording unit of Figures 1 to 9.

Figure 11 is a cross-sectional view of the transmitter of Figure 10 taken on line 11—11 of Figure 14, looking in the direction of the arrows and showing the optical system of the transmitter unit.

Figure 12 is a view of the transmitter of Figure 10 taken on line 12—12 of Figure 14 looking in the direction of the arrows and showing the operating mechanism of the transmitter of Figure 10.

Figure 13 is a cross-sectional view taken on line 13—13 of Figure 14 looking in the direction of the arrows.

Figure 14 is a top view of the mechanism of the transmitter taken on line 14—14 of Figure 11 looking in the direction of the arrows.

Figure 15 is a view, partly in cross-section, taken on the line 15—15 of Figure 11 looking in the direction of the arrows.

Figure 16 is a top plan view, partly in cross-section, taken on line 16—16 of Figure 10 showing the manner in which the transmitting tape is fed through the mechanism looking in the direction of the arrows.

Figure 17 is a view of the edge of the light chopping disk taken from line 17—17 of Figure 15.

Figure 18 is a fragmentary enlarged view of a portion of the face of the light chopping disk of Figure 15 and is taken from line 18—18 of Figure 17.

In Figures 1 to 9 inclusive, I have shown my novel simplified high speed facsimile tape recorder; and in Figures 10 to 18 I have shown my tape transmitter which is arranged for cooperation with my tape recorder to form an efficient high speed tape transmitting and recording system.

Referring now to Figures 1, 2 and 3, I have here shown the basic operating mechanism of my recorder which is housed in a casing 29 having a base 21 and a horizontal partition 22 defining a drawer receiving compartment 23 and an upper compartment 24 which encloses the essential portions of the mechanism.

The upper portion of one side of the housing 20 is closed by a cover 26 (Figures 1 and 2) which is recessed with respect to the cover portion 27 in order to provide the ledge or surface 28 over which the tape recording paper 29 may be fed.

A motor 32 (Figures 1 and 3) is mounted on a platform 33 which is positioned in any suitable manner on the partition 22 and which may in addition be supported from a wall of the housing. The motor drives shaft 35 which rotates in suitable bearings 36 and 37 and projects through the side cover 26 over the ledge 28. A "lawn-mower" type recording element 40 having the spiral 41 is mounted on the end of shaft 35 and is rotated thereby.

Different portions of the paper tape 29 may be successively brought into contact with the recording element 40 in accordance with received telepicture impulses in the manner hereinafter described. The recording element or "lawn-mower" 40 rotates in contact with the ink spreading roll 50 which in turn is in contact with the ink supply roll 51; the latter rolls are rotatably mounted on the supporting bar 53 which in turn is carried by the pin 54 on the side cover member 26. Roll 51 is preferably a perforated metal roll, the surface of which is covered with felt and the interior of which is supplied with ink. Roll 50 is preferably a rubber covered ink spreader roll which receives the ink from roll 51 and applies it to the spiral 41 of the recording element 40. Both rolls 50 and 51 rotate by reason of the contact of roll 50 with the rotating recording element 40.

The recording tape 29 is drawn from a supply roll 60 in the drawer 61 in compartment 23. The tape 29 is led through slot 63 in the drawer side and through the slot 64 in the casing side around the roller 66, then along the ledge or platform 28, under the recording element 40, between the draw roll 70 and the pressure roll 71 and thus out of the machine. The projecting end 75 of the tape 29 may then be read, torn off and filed or rolled up on a suitable roll.

Suitable guides may be provided on the ledge 28 for the tape; and the bearing 76 carrying roll

66 may also be extended to provide a guide for the tape to ensure that the same passes beneath the "lawn-mower" 40.

The draw roll 70 is mounted on shaft 80 which is rotated in its bearings 84 and 85 by the shaft 81 through bevel gears 82 and 83. Shaft 81 is rotated in its bearings 86 and 87 by the worm gear 88 mounted on shaft 35 meshing with the spiral gear 89 mounted on shaft 81.

Pressure roll 71 is rotatably mounted on the bar 95 which is pivotal on pin 96 carried by the side cover 26. Pressure is maintained by a tension spring 97 connected at one end to the bar 95 and at the other end to the side cover.

The ledge or platform 28 is slotted at 100 so that the rolls 70 and 71 may engage the tape 29 between them to draw the same continuously beneath the recording element 40.

As seen in Figure 9, the drawer 61 and hence the supply roll 60 fills almost the entire bottom compartment 23. The drawer is provided with a finger hole 110 (backed by an inside dust-excluding cover 111) which may be used to open the drawer. The slot 63 in the drawer side may be made sufficiently long to enable the tape 29 to be threaded through the slot 64 in the casing while the drawer is partly open.

The recording tape or paper 29 passes beneath the recording element 40, but, in its ordinary position, is not in contact with the spiral rib 41 thereof. A slot 120 is provided in the ledge or platform 28 immediately beneath the recording element. The slot is arranged normal to the path of movement of the paper and parallel to and directly beneath the axis of rotation of the recording element 40. The paper passes over the slot and is slightly narrower than the length of the slot.

A recording bar or knife 122 is mounted beneath the slot 120 and is so arranged that it may rise and fall through the slot and successively press the different portions of the tape or paper 29 up against the recording element 40 to receive an impression from the spiral rib 41 thereof.

The recording knife is, of course, actuated to rise and fall in accordance with incoming facsimile signals. The knife, when it rises, will press the paper against the inked spiral 41 to produce a dot on the paper at each point where the knife edge intersects the spiral. In the case here shown, the spiral is so arranged that three spaced dots will be so produced each time the knife rises. Consequently, the received message will be recorded on the tape in three identical parallel lines. The angular position of the recording element 40 at the time the knife strikes the paper against its spiral will determine the relative position of successive dots in each line. With the transmitting and receiving tapes moving at even approximately the same speed, the successive dots on the receiving tape will be sufficiently juxtaposed to provide a record of the message written on the transmitting tape. The recording of the message in three lines ensures that, even in the event of such lack of synchronism as to result in splitting of the message of one line between the top and bottom of the tape, there will always be one full message carrying line on the tape. The use of such a three line recording method which obviates the necessity for maintaining exact synchronism is shown in Patent No. 2,046,328 and the use of a three flight spiral recording rib for this purpose thus constitutes no part of the present invention.

The knife 122 must thus be mounted in such a

manner as to be readily oscillatable while at the same time it must always be in registry with the slot and parallel to the axis of rotation of the recording element 40.

A form of mounting which has been found successful is shown in Figures 3, 5 and 7. The knife 122 is spot-welded to a flange 125 of the flat spring metal member 126.

The opposite end of member 126 is secured by the pair of bolts 127 to the flange 128 of the bracket 129 which is secured to the underside of ledge 28. Member 126 is made substantially triangular in form in order to reduce its weight; and is also provided with holes 132 for this purpose. The rigid securing of the knife 122 to member 126 and the rigid securing of member 126 to bracket 129 thus positively positions the knife with respect to the slot, the tape and the recording element. The spring metal material of the member 126 permits the knife to be readily raised and lowered.

Knife 122 is provided with a clevis 140 to which is pivotally secured one end of rod 142, the other end of which is pivotal in the clevis 144 of the extension 146. Extension 146 is preferably made of non-magnetizable material and is rigidly secured to the armature 148 which is of magnetizable material.

The armature 148 is preferably riveted to a milled portion of the pin 150 which is rotatable in bearings 151 and 152 of the magnet supporting frame 154 which is, in turn, appropriately secured to a magnet base plate 160. Bearings 151, 152 are defined by inset members 155, 155 (Figures 4 and 7) held on the frame by bolts 159.

Clamping screws 182 passing through top member 175 securely position this pole with respect to the other elements of the device. A permanently magnetized bar 184, preferably of cobalt steel, is secured to the pole piece 178 by the countersunk bolt 185, and is also secured to pole piece 187 by a similar countersunk bolt 188.

The upper end of frame 154 is provided with an opening 177 which receives pole 178 of a permanent magnet 180.

The armature 148 as has above been pointed out is made of magnetizable material but is not permanently magnetized. The pole pieces 178 and 187 of the permanent magnet 180 are, however, permanently magnetized and have a specific polarity. Thus, for purposes of illustration, the pole piece 178 may be taken as north and the pole piece 187 as south. The coils 190 and 191 carried by the coil carrying frame 170 (which in turn is positioned by frame 154) surround the armature 148 and are arranged so that when energized they will induce a magnetic field in the armature having a predetermined polarity.

Thus, when the coil 191 is energized, end 193 of the armature will be the south pole thereof and end 194 will be the north pole. Consequently, the armature will tend to rotate in a counter-clockwise direction, thus pulling down the rod 142 and pulling down the knife 122.

When coil 191 is deenergized and coil 190 is energized, the polarity of the armature 148 will be reversed and end 194 thereof will become the south pole and end 193 will become the north pole; hence the armature will rotate in a clockwise direction, thus raising the rod 142 and raising the knife 122.

When the knife is thus raised, it will, as previously described, press the tape 29 against the spiral rib 41 of the recording element to produce a plurality of dots in the manner above set forth.

I have found it necessary in the present invention in order to obtain high speed recording that the armature be positively actuated in each direction. Thus, rather than depend on the energization of a coil to raise the armature and de-energization thereof to permit a spring to retract the same or retract the knife blade, I have found that the alternate energization of coils wound in opposite directions will permit a faster rate of movement of the knife blade in each direction than would otherwise be obtained.

In the operation of my apparatus, therefore, the coil 191 is ordinarily constantly energized in order to maintain the end 194 of the armature in the depressed condition, thus maintaining the knife blade 122 away from the recording element 40.

When a facsimile signal is received which is to be recorded as a black dot, the coil 191 is de-energized and coil 190 is immediately energized to result in a raising of the end 194 of the armature and of the knife blade 122. Coils 190 and 191 are connected to a suitable push-pull circuit so that they may be readily energized or de-energized as the occasion may require.

By the simple means herein set forth, the polarity of the armature 148 may be rapidly and continuously reversed in order to cause the end 194 thereof to be attracted to one pole or the other of the permanent magnet, thus resulting in rapid raising or lowering of the knife 122.

After the apparatus of my invention has been set up, it may be necessary at times to adjust the base plate 160 of the magnet operating elements 35 in order to provide a proper spacing between the edge 122 of the knife and the edge of the rib 41. For this purpose, the base plate 160 of the magnetic structure may be made readily adjustable both with respect to height and with respect to 40 its longitudinal position in the structure.

Thus, the screws 200 which serve to secure the base plate 160 to the upper side of the partition 22 may pass through longitudinal slots 201 in the base plate 160 to permit the base plate 160 to be longitudinally adjustable.

The screws 200 enter into tapped perforations in the horizontal partition 22 and thus secure the base plate 160 thereto. The end 205 of the base plate 160 may also be readily raised and lowered in order to adjust the position of the knife 122 with respect to the rib of the recording element 40 so that a proper stroke may be obtained.

For this purpose, an adjusting screw 207 is provided at the end 205 passing through a tapped opening 208 in the base plate 160 and bearing against the upper surface of the partition 22. Rotation of the screw in one direction or the other will result in raising or lowering of that end of the base plate. The opposite end of the base plate is provided with rounded lugs 210 which have slots registering with the slots 201 at the superposed end of the base plate to permit the screws 200 at that end to pass therethrough. These rounded lugs 210 permit the plate to rock at the end 212 as the opposite end 205 is raised or lowered.

In order to obtain an adjusting operation in this manner, all of the screws 200 are first loosened and the plate 160 is moved back and forth as may be necessary to obtain the optimum position of the armature 148 and the rod 142 with respect to the knife 122. When this position is located, then if the knife 122 is not at the optimum distance from the recording element 40, the adjust-

ing screw 207 may be operated to raise or lower one end of the base plate until this optimum distance is obtained.

When the base plate has thus been adjusted so that the elements are appropriately arranged for optimum distance of the knife blade from the recording element and for optimum positioning of the armature 148 and rod 142 with respect to the knife blade, then the screws 200 are all tightened and the position of the base plate 160 is fixed.

The operation of the recording unit of my invention should now be obvious:

The tape is led from the supply roll 60 under the roller 64 up the outside of the machine over the roll 66; beneath the recording element 40 and through the draw rolls 70 and 71. Operation of the motor now causes the draw rolls to rotate continuously, moving the tape 29 at constant speed from the supply roll beneath the recording element 40 to the outside of the machine. The motor as previously described not only causes the draw rolls to operate but also effects the constant rotation of the recording element or "lawnmower" 40.

Coil 191 is energized to cause the armature 148 to be biased in a counterclockwise direction to draw the knife away from the tape. As facsimile impulses are received, coil 191 is deenergized and coil 190 energized each time such an impulse is received to cause the knife 122 to rise. When the momentary facsimile impulse ends, the coil 190 is deenergized and coil 191 energized to pull the knife away from the lawnmower.

The facsimile impulses are received from the transmitter which scans a tape of similar size moving at substantially the same speed as the tape 29. Consequently, the angular position of the recording element 40 when the knife blade rises will predetermine the position of the dot on the tape with respect to the edges thereof.

As previously pointed out, as long as the transmitting and recording tapes are moving at approximately the same speed, the successive dots on the recording tape will correspond to successive portions of the message written on the transmitting tape.

Owing to the fact that a three flight spiral is used on the "lawnmower" recording element, the angular position of the "lawnmower" at the time of the inception of message reception is not important. By the use of this type of spiral, the message is recorded in three lines and should any of these lines be split between the top and bottom of the receiving tape at least one full line of message material will appear. A readable message will thus be obtained as long as there is only approximate synchronism between the transmitting and recording mechanism.

Experiments have shown that the recording and transmitting tapes may be out of synchronism by as much as 10% or even more while still permitting the recording of a readable message. Even greater differences in speeds of movement of the tapes at each end of the facsimile system will nevertheless result in a message which can with a little care be made intelligible at the receiving end. Since, however, the maintenance of synchronism within an allowable error of plus or minus 10% presents no problem at all even in units which are to be operated under extremely rough conditions, my invention provides an efficient means for transmitting and receiving written messages at high speeds.

The essence of the improvement in my recorder lies not merely in the combination of the

specific elements described but lies also in the compactness and inherent ruggedness of the unit which has been made to occupy an overall space of 8 by 9 by 6 inches.

Heretofore, in the operation of devices of this character, where springs have been used either to attract or withdraw the knife element, any shock which was imparted to the mechanism often resulted in false operation of the spring or in permanent distortion thereof. Also after a series of messages transmitted at the highest possible speed, the spring tended to lose its resiliency, thus making it necessary to slow up transmission or reception or rendering the recorder completely inoperative for the purpose of receiving intelligible messages.

In the present device, the knife blade is positively urged in each direction by a rugged structure comprising the permanent magnet and the coils previously described. False operation of the unit is positively prevented since one coil serves positively to maintain the armature in the non-recording position until a facsimile impulse is received when that coil is de-energized and another coil operates the armature to the recording position.

The unit itself as has above been pointed out is contained in a casing which almost fully encloses the same. The only exposed portion is the platform or ledge 28 with the printing and pressure roll thereon. An appropriate cover may be provided for this platform, having an appropriate slot through which the end 75 of the recording tape 29 may be drawn. The placement of this cover on the casing 26 will complete the cubical form of the casing.

The operator, therefore, once the paper has been appropriately threaded through the elements, need pay no attention to the device whatever except to read the message which emerges therefrom.

This form of structure may obviously be mounted in any position on the vehicle and may operate equally well if mounted on its side or even upside down.

The device is intended primarily to be operable from a radio receiving set to which it may be connected in any suitable manner. All that is necessary is that the coils 190 and 191 be connected to the push-pull amplifying circuit of the radio receiver.

The motor is intended to be driven from any suitable local source. It may be constantly driven in the vehicle in which it is mounted or may be brought into operation by the operator when he is informed that the message is to be transmitted; or it may be arranged so that a suitable impulse transmitted through the radio receiving set will initiate operation of the motor and effect the closing of a clutch between the motor and the shaft 35.

Primarily, as has been pointed out above, the device is intended for use in moving vehicles—reconnaissance cars, tanks, tank destroyers, airplanes and the like wherein the unit may be subjected to extreme mechanical shocks.

Consequently, the recording unit has been arranged with the smallest possible number of moving parts, is of rugged construction and is small and compact.

The transmitting unit which is also adapted for use in vehicles and which is peculiarly fitted for operation with the recording unit thus far described is more specifically shown in Figures 10 to 18.

The transmitting element, as shown in Figure

10, comprises a housing 230 enclosing all of the operating mechanism. The housing is, however, provided with a recess 231 at one side having a base 232 over which the tape 233 carrying the message to be transmitted may be passed.

The tape 233 is fed on the surface 232 beneath the guide plate 235 and under the pressure roll 236 and is then drawn out. As is seen in Figure 16, the guide plate may be secured to the surface 232 by means of suitable screws 238 spaced sufficiently to clear the side edges of the tape 233. The guide plate 235 is provided with the slot 240 so that a portion of the tape may be exposed, as it passes through, to a light beam which is reflected into the lens system of the transmitting unit.

The pressure roll 236 is mounted on a bar 242 which is rotatable on the pin 243 carried by the housing and is maintained in appropriate pressure engaging position by the compression spring 244 captured between a portion of the housing and the perforation 245 in the upper surface of the bar 242. The tape 233 carrying the message may be threaded under the plate 235 and the pressure roll 236 and drawn through by hand at a relatively constant rate or a motor may be provided to draw the tape through at a more exactly constant rate. The latter arrangement is preferred in order to obtain approximate synchronism and is hereinafter described.

The procedure, as far as the operator is concerned, is simply that of writing or typing the message on the tape 233, threading the same under the guide plate and pressure roll, placing a cover over the recess 231 and starting the machine so that the tape is pulled through and scanned. The message, of course, is written in a contrasting color on the tape. The tape itself may be of any suitable material, such as ordinary white bond paper or may even be of a lesser grade and the writing is preferably to be done in a clear dark black.

One or more sources of light may be provided to focus the light spot on the portion of the tape passing beneath the slot 240 in the guide plate 235.

As is seen in Figure 13, the light sources comprise a pair of light bulbs 250, 250 which are positioned in any appropriate manner in the sockets 252, 252 carried by appropriate supporting members 254, 254 in the housing and connected to a suitable source of energy. The light from the bulbs 250 is focused through the cylindrical lens focusing systems 260 to the portion of the tape 233 exposed through the slot 240 in the plate 235.

The cylindrical lens 260 results, not in the creation of a simple light spot, but rather in the formation of a narrow rectangle of light at the slot 240 so that the entire width of the message written on the tape is thus brightly lighted. The bulbs are so arranged that the filament 262 in each thereof is substantially parallel to the axes of the respective cylindrical lenses to provide an even illumination of the entire slot.

The light is reflected, as seen in Figures 13 and 11, from the narrow portion of the tape that is illuminated into the lens systems 270 and is focused thereby through the prism 271 (which changes its direction) into the photoelectric cell 272.

Two light sources are shown in the present device since the arrangement of the cabinet of the transmitter provides the room therefor and the brightness of the reflected beam is thus ensured. Only one such light source is actually essential. Two light bulbs may, however, be provided so that the machine will continue to operate for 75

transmitting purposes even if one of the light bulbs should fail.

The lens system 270 is intended to focus a narrow rectangle of light on the photoelectric cell and in order to achieve as bright a columnated beam as possible, the lens system 270 may be appropriately focused by rotating the objective thereof on its threaded mounting 275.

It is necessary in order to achieve the transmission of facsimile impulses that the light beam that is reflected to the photoelectric cell be chopped into a series of rapidly recurring impulses to create a suitable frequency wave which will modulate the transmitting wave or current and which will in turn be modulated to operate the armature 148 in the recording unit to cause the knife to rise and fall. A grid may be interposed in or behind slot 286 for this purpose.

A continuously rotating scanning disk 280 (Figures 11, 12, 14 and 15) is provided. The disk 280 comprises a metallic circular element having a plurality of spaced slots 281 in the periphery thereof. Each of the slots 281 passes in front of an opening (hereinafter described) in front of the photoelectric cell 272 and the light passes through the slot to impinge on the photoelectric cell—so that each portion of the rectangle of light is successively scanned while the paper is moving.

The photoelectric cell 272 is provided with a housing 283 having an opening 284 therein. The opening 284 is covered by the thin rectangular sheet 285 in which the narrow vertical slot 286 (Figure 15) is provided. The covering sheet 285 is of very thin material, preferably of the order of 3 mils in thickness, so that the intensity of the light passing therethrough will not be appreciably diminished (by absorption against the sides of slot 286) where the light passes through at an angle less than perpendicular to the sheet.

Similarly, the disk 280 is milled at the areas 288 adjacent each slot 281 to reduce the thickness of the edges of the disk defining the slot 281 for the same purpose.

The opening 284 in front of the housing which is covered by the sheet 285 is provided with bevelled edges as shown in Figure 11 in order to permit the maximum of light to reach the photoelectric cell without being reflected from the sides of the opening 284.

The light reflected from the tape into the photoelectric cell is, as is seen in Figure 15, chopped into a series of impulses of a predetermined frequency by the passage of the successive slots 281 in the disk past the slot 286 and the aforementioned grid in the cover plate 285 in front of the photoelectric cell 272.

The motor 300 is mounted in any suitable manner, as for instance, by the bolts 301, 301 on the base 302 of the apparatus. Motor 300, as seen in Figure 12, drives the gear wheel 304 which meshes with the drives gear wheel 305. Gear wheel 305 is keyed to shaft 306 which drives the disk 280 which is mounted thereon.

The mounting ring 310 of the disk 280 carries the gear teeth 311 which drive the spiral gear 313 mounted on the vertical shaft 314 which rotates in the bearing 315. Vertical shaft 314 is provided with a worm gear 316 which drives the gear wheel 318 mounted on shaft 319 which in turn drives the draw roll 320 beneath the platform 232. The draw roll 320 is engaged by the pressure roller 236 so that the tape 233 is pressed thereagainst and so that the tape may thereafter be drawn through at a predetermined speed by the motor. Slot 322 is provided in the platform 232 so that

the pressure and draw rolls may engage opposite sides of the tape to feed the same through the device.

The motor 300 is operated in at least approximate synchronism with the motor on the receiver or recorder so that the respective tapes at each end move at at least approximately the same speed.

Since the efficiency and usefulness of the present device depends on the transmission of 180 inches of message tape per minute and since clarity can be achieved with a minimum of 60 lines per inch, it is apparent that the disk 280 must rotate at a speed which will permit the slots to pass in front of the aperture 286 at the rate of 180 slots per second.

It will be obvious, of course, that the energy generated by the impingement of the light on the photoelectric cell will be used to modulate the transmitted wave from the radio transmitter in order to transmit the facsimile impulses to the radio receiver to which the facsimile recorder is connected.

In the operation of the device, it is, of course, clear that the tape 233 is first threaded by the operator beneath the plate 235 and the pressure roll 236. The side of the machine is then covered so that no stray light may be permitted to affect the operation of the device and the transmission is begun.

As the portions of the message are continuously successively presented beneath the opening 240 and the light focused thereon is reflected to the photoelectric cell, the light is chopped into a series of impulses. The photoelectric cell may be so connected that the transmitter will emit a facsimile impulse either when light is reflected to the photocell or when light is not reflected thereto.

Preferably, since the transmitted message is to be written in black and white, the facsimile impulse is to be transmitted for recording when a reduced amount of light is reflected to the photocell.

Thus, as seen in Figure 15, light is impinged on the photocell when any one of the slots 281 in the disk passes across the slot 286 in the cover sheet 285. The intersection of these two slots in the light path produces a light spot which may be impinged on the photocell. The light spot travels from the top of the slot 286 to the bottom of the slot 286, thus successively scanning every portion of the light beam.

The slots 281 are necessarily sufficiently long so that despite the curvature of the disk 280, the two slots will intersect in the light path over the entire length of the slot 286.

Accordingly, the length of the facsimile impulse is determined by the length of time which it takes for one of the slots 281 to pass across the slot 286 and the spacing between impulses is determined by the spacing between successive slots 281.

As will be seen, the spacing is only short enough appropriately to define a sinusoidal current wave which may be used to modulate the transmitter carrier wave.

The transmitting device of Figures 10 to 18 is, as will be obvious, compact and rugged and does not require the operation of any delicate elements such as springs and the like. The scanning operation is obtained simply by the movement of the tape through the machine and the scanning or light chopping disk is a simple rotatable member.

The entire unit may occupy a space of no more than 8 by 9 by 6 inches and may be connected to the ordinary transmitting set in a vehicle such as a tank or reconnaissance car or a boat or airplane.

In the operation of my transmitter and receiver, it is intended primarily that the transmitter be located in a command car or other vehicle while the receiving units be located in the vehicles which are subject to the orders emanating from the command car.

In the ordinary operation of tanks and certain types of military operation in connection with other vehicles, the noises encountered are such as virtually to prevent radio communication by aural means. The primary object of the present device is first to provide a means of communication which will permit of the immediate transmission of permanent written messages which require no aural perception of any kind, and secondly to render the means of communication secret whereby the messages cannot be intercepted unless specific equipment is used.

The fact that the message is permanent as well as visual makes it possible for the crew of the receiving vehicle to receive the message even at a time when their attention must necessarily be directed to an emergency condition and to defer the reading of the message until such time as the immediate emergency requiring absolute attention of each member of the crew is passed. This is impossible, of course, in the case of aurally perceptible messages and is necessarily a distinct advantage thereof.

In addition, there is no possibility that the message will be misunderstood, as will necessarily occur in the case of aural messages which are delivered in the heat of battle, since the message may be studied and reread before the instructions therein are carried out.

It is obvious, of course, that owing to the small size of the facsimile system of my invention, a transmitting and receiving unit may be mounted in any vehicle having a radio transmitter as well as a receiver, so that intercommunication among all such vehicles will be possible.

While my device has been developed primarily for use between moving vehicles and between moving vehicles and a central station, it is obvious that it is not necessarily limited to this use but may be used for point to point communication.

While my device is also peculiarly adaptable for use in connection with radio transmission and reception, it is also clear that it will function equally well over wired connections.

It is also obvious that variations may be made in the device, for instance to integrate the transmitting and receiving units into a single structure operable from a common motor. In the latter case the motor may be provided with suitable alternate clutch or other connecting arrangement to operate either the transmitter or the recorder at will or the elements may be operated simultaneously so that, when transmitting, a written record may be made of the quality of reception.

In the foregoing I have illustrated my invention only in connection with specific embodiments thereof which have been found practical. Many variations and modifications of the foregoing should, however, now be obvious to those skilled in the art. Accordingly, I prefer to be bound not by the specific disclosures herein but only by the appended claims.

I claim:

1. A facsimile tape transmitter comprising a pair of light sources; a support for a tape; means for focussing the light from both sources in a single rectangular light bar of predetermined width on said tape; said rectangular bar of light extending transversely of said tape; means for moving said tape with respect to said bar of light; a light sensitive element; means for focussing and directing the light reflected from said tape on said light sensitive element; and a rotatable light chopper disk mounted between said last mentioned focussing means and said light sensitive element.

2. A facsimile tape transmitter comprising a light source; means for moving a tape with respect to said light source; means for focussing said light in a rectangular light bar of predetermined width on said tape; said rectangular bar of light extending transversely of said tape; a light sensitive element; means for focussing and directing the light reflected from said tape on said light sensitive element; and a rotatable light chopper disk mounted in said light path; said light chopper disk comprising a series of radial slots adjacent the periphery thereof; said slots on rotation of the disk being successively interposable in the light path; and means for reducing the amount of light absorption and reflection from the sides of the slots; said means comprising the formation of a relatively thin section in said disk in the area defining each slot.

3. A facsimile tape transmitter comprising a light source; means for moving a tape with respect to said light source; means for focusing said light in a rectangular light bar of predetermined width on said tape; said rectangular bar of light extending transversely of said tape; a light sensitive element; means for focusing and directing the light reflected from said tape on

10

said light sensitive element; and a rotatable light chopper disk mounted in said light path; said light chopper disk comprising a series of radial slots adjacent the periphery thereof; said slots on rotation of the disk being successively interposable in the light path; and means for reducing the amount of light absorption and reflection from the sides of the slots; said means comprising spaced milled sections of the chopper disk around the periphery thereof forming spaced relatively thin areas in said chopper disk, said slots extending in said milled sections.

4. In a facsimile transmitter, a light chopper disk comprising a series of slots; and means for reducing the light absorption and reflection from the sides of the slots; said means comprising spaced milled sections of the chopper disk forming spaced relatively thin areas in said chopper disk, said slots extending in said milled sections.

5. In a facsimile transmitter, a light chopper disk comprising a series of radial slots communicating with the periphery thereof; and means for reducing the light absorption and reflection from the sides of the slots; said means comprising spaced milled sections of the chopper disk around the periphery thereof forming spaced relatively thin areas in said chopper disk, said slots extending in said milled sections.

FRANK R. BRICK.
